Attorney

UNITED STATES PATENT OFFICE.

JOHN LUKASZEWSKI, OF CHICAGO, ILLINOIS.

GAS OR LIQUID-FUEL BURNER.

1,395,196.

Specification of Letters Patent.

Patented Oct. 25, 1921.

Application filed December 31, 1920. Serial No. 434,338.

To all whom it may concern:

Be it known that I, JOHN LUKASZEWSKI, a citizen of the United States of America, residing at Chicago, in the county of Cook 5 and State of Illinois, have invented certain new and useful Improvements in Gas or Liquid-Fuel Burners, of which the following is a specification.

This invention relates to certain new and 10 useful improvements in gas or liquid fuel burners, particularly adapted for use in starting fires although capable of general application.

The primary object of the invention is to 15 provide a burner of the above kind which may be easily inserted beneath the grate of a stove so that a plurality of burner members may project upwardly between the spaces between the bars of the grate for efficiently lighting the material on the grate 20 which is employed for starting a coal fire or the like.

A further object of the invention is to provide the burner with burner members having 25 adjustable outer shells whereby the mixing chamber of each burner member may be regulated in size for varying the intensity of the flame thereof.

A further object of the invention is to so 30 construct each burner member that the air, in passing to the mixing chamber moves parallel with the liquid or gaseous fuel so as to guard against impeding the movement of the latter throughout the outlet of the 35 burner, whereby most efficient results are obtained.

With these general objects in view and others that will appear as the nature of the invention is better understood, the same consists 40 in the novel construction, combination and arrangement of parts hereinafter more fully described, illustrated in the accompanying drawings, and pointed out in the appended claims.

45 In the drawings forming a part of this application and in which like designating characters refer to corresponding parts throughout the several views:

Figure 1 is an elevational view of the preferred form of burner constructed in accordance with the present invention and shown connected to a liquid fuel tank which is partly broken away by means of a flexible conduit or hose which is also partly broken 55 away,

Fig. 2 is an enlarged sectional view taken substantially upon line II—II of Fig. 1,

Fig. 3 is an enlarged transverse sectional view taken substantially upon line III—III of Fig. 2, and

Fig. 4 is a view partly in elevation and partly in section, of a modified form of the burner *per se*.

Referring more in detail to the several views, the present invention preferably embodies a burner construction including an inlet pipe 5 adapted as at 6, at its outer end to be coupled to a flexible conduit or hose 7 which has its opposite ends coupled as at 8 to a liquid fuel tank 9 having a valve 10 for controlling the flow of liquid therefrom. In practice, kerosene is preferably employed as the fuel, and if an intense flame is desired, the pipe 5 is provided with a branch pipe 11 adapted to have its outer end coupled to a suitable pipe extending to a source of steam supply.

The burner *per se* includes a manifold or transverse pipe 12 centrally fixed to the inner end of the pipe 5 and communicating with the latter as well as having a plurality of spaced fuel pipes extending laterally therefrom as at 13 in the same general direction as the pipe 5 but from the opposite side of the manifold 12. The outer end of each pipe 13 is flanged as at 14, and this flange is provided with external threads so as to have an internally threaded combined sleeve and burner tip 15, threaded thereon whereby a mixing chamber 16 is formed within the member 15 between the outlet opening 17 of the latter and the flange 14.

The sleeve and burner tip 15 is of comparatively great length so as to surround a major portion of each pipe 13, and an annular space is left between the pipe 13 and its sleeve 15 for permitting inlet of air. The air passes into the open lower end of the sleeve 15 and moves parallel with the fluid in the pipe 13 and is allowed to pass into the mixing chamber while traveling in the same direction by the provision of a plurality of openings 18 in the flange 14. By adjusting the combined burner tip and sleeve 15 as indicated by dotted lines in Fig. 2, the mixing chamber 16 may be varied in size for varying the intensity of the flame and for enabling lengthening of the burner members when the latter are found of insufficient length to pass above the grate bars of a stove. If desired, the

steam pipe 11 may be provided with a control flange 19.

Referring to Fig. 4, a simplified form of the invention is shown which will be found of ample efficiency in starting fires for domestic purposes. In this form of the invention the pipe 5' is adapted to have its outer end coupled to a liquid supply tank in the manner described with respect to pipe 5 in the form shown in Fig. 1, and the inner end of this pipe is connected to and communicates with the central portion of a transverse pipe or manifold 12' having a plurality of laterally extending burner pipes 13'. In this form of the invention steam is not employed for promoting combustion or feeding the fuel under pressure, and if desired, the pipe 11 may also be dispensed with in the form of Fig. 1.

While the form of the invention herein shown and described is what is believed to be the preferred embodiment thereof, it is nevertheless to be understood that various forms, modifications and arrangements of the parts may be made without departing from the spirit and scope of the invention as claimed.

Having thus described my invention, what I claim as new and desire to secure by Letters Patent, is:

1. A gas or liquid fuel burner including an inlet pipe adapted to have its outer end coupled by a flexible conduit to a fuel supply, a transverse manifold having its central portion rigid with and communicating with the inner end of said pipe, a plurality of burner pipes extending from the opposite side of the manifold in the same general direction as said first named pipe and arranged in spaced relations so as to pass upwardly between the grate bars of a stove grate, said burner pipes being provided with flanged upper ends having longitudinally extending openings therethrough, and a combined sleeve and burner tip mounted upon the flange of each burner pipe in spaced relation to the latter whereby air is admitted between the burner pipe and the sleeve and through the openings in the flange in the same direction as the flow of the fuel through the burner pipes, said combined sleeve and burner tip having a restricted opening in the outer end thereof and providing a mixing chamber between said restricted opening and the open upper end of the burner pipe.

2. A gas or liquid fuel burner including an inlet pipe adapted to have its outer end coupled by a flexible conduit to a fuel supply, a transverse manifold having its central portion rigid with and communicating with the inner end of said pipe, a plurality of burner pipes extending from the opposite side of the manifold in the same general direction as said first named pipe and ar-

ranged in spaced relations so as to pass upwardly between the grate bars of a stove grate, said burner pipes being provided with flanged upper ends having longitudinally extending openings therethrough, a combined sleeve and burner tip mounted upon the flange of each burner pipe in spaced relation to the latter whereby air is admitted between the burner pipe and the sleeve and through the openings in the flange in the same direction as the flow of the fuel through the burner pipes, said combined sleeve and burner tip having a restricted opening in the outer end thereof and providing a mixing chamber between said restricted opening and the open upper end of the burner pipe, said combined sleeve and burner tip being adjustable longitudinally of and relative to said burner pipe.

3. A gas or liquid fuel burner including an inlet pipe adapted to have its outer end coupled by a flexible conduit to a fuel supply, a transverse manifold having its central portion rigid with and communicating with the inner end of said pipe, a plurality of burner pipes extending from the opposite side of the manifold in the same general direction as said first named pipe and arranged in spaced relations so as to pass upwardly between the grate bars of a stove grate, said burner pipes being provided with flanged upper ends having longitudinally extending openings therethrough, a combined sleeve and burner tip mounted upon the flange of each burner pipe in spaced relation to the latter whereby air is admitted between the burner pipe and the sleeve and through the openings in the flange in the same direction as the flow of the fuel through the burner pipes, said combined sleeve and burner tip having a restricted opening in the outer end thereof and providing a mixing chamber between said restricted opening and the open upper end of the burner pipe, said combined sleeve and burner tip having threaded connection with the flange of its restrictive burner pipe for adjustment longitudinally on and relatively to the burner pipe, whereby variations in the size of the mixing chamber may be had with a consequent lengthening or shortening of the burner members.

4. A gas or liquid fuel burner including an inlet pipe adapted to have its outer end coupled by a flexible conduit to a fuel supply, a transverse manifold having its central portion rigid with and communicating with the inner end of said pipe, a plurality of burner pipes extending from the opposite side of the manifold in the same general direction as said first named pipe and arranged in spaced relation so as to pass upwardly between the grate bars of a stove grate, said burner pipes being provided with flanged upper ends having longitudinally

extending openings therethrough, a combined sleeve and burner tip mounted upon the flange of each burner pipe in spaced relation to the latter whereby air is admitted 5 between the burner pipe and the sleeve and through the openings in the flange in the same direction as the flow of the fuel through the burner pipes, said combined sleeve and burner tip having a restricted opening in 10 the outer end thereof and providing a mixing chamber between said restricted opening and the open upper end of the burner pipe, said combined sleeve and burner tip having threaded connection with the flange of its restrictive burner pipe for adjustment 15 longitudinally on and relatively to the burner pipe, whereby variations in the size of the mixing chamber may be had with a consequent lengthening or shortening of the burner members, and a branch steam inlet 20 pipe provided on the first named pipe and having a control valve therein.

In testimony whereof I affix my signature.
JOHN LUKASZEWSKI.
